ATTORNEYS

UNITED STATES PATENT OFFICE.

JAMES MADISON JACKSON, OF PARKERSBURG, WEST VIRGINIA.

FLOOR BOARD.

Application filed November 20, 1924. Serial No. 751,116.

To all whom it may concern:

Be it known that I, JAMES MADISON JACKSON, a citizen of the United States, and a resident of Parkersburg, in the county of Wood and State of West Virginia, have invented certain new and useful Improvements in Floor Boards, of which the following is a specification.

This invention relates to moldings for binding the edges of floor boards of automobiles and has for its object the provision of a device for not only binding the floor boards but for lubricating the adjacent edges to prevent objectionable noises and for maintaining the boards against rattling.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a fragmentary view in perspective of a front portion of an automobile showing my invention applied to the floor boards.

Figure 2 is a vertical transverse sectional view of my anti-rattling device.

Figure 3 is a transverse vertical section showing my device applied to a plurality of floor boards.

Referring more particularly to the drawings, 1, 2 and 3 designate the floor boards of an automobile located adjacent the front seat of an automobile which are ordinarily bound with a metal molding and as usually constructed either have sufficient space between them to prevent squeaking from friction but permit the boards to rattle or they are spaced sufficiently close together to prevent rattling but nevertheless cause noises because of friction. In order to prevent rattling and noises from friction I have formed a U-shaped channel member generally designated by the numeral 4 which has a side wall 5 of greater height than the other side wall 6. The lower ends of the wall are connected together by a curved member shown at 7 to form a container to hold a

predetermined quantity of lubricant and the width between the lower end of the wall is less than the distance between the extreme upper edge 8 of the wall 6 and the portion of the wall 5 which is directly opposite. In other words, the wall 6 is bent outwardly at its upper edge from the wall 5. Screws or nails 9 are adapted to secure the wall 5 to one edge of a floor board, the other wall 6 being seated within an inclined pocket 10 formed in the edge of an adjacent floor board.

The device is formed of a single piece of sheet metal and is bent outwardly at substantially right angles to the wall 5 as shown at 11 and then returned upon itself as at 12 with an inner flange 13 bent towards the flange 11 and located in substantially the same plane with said flange, the flange 13 being located below the top 12 and resting upon the upper surface of a floor board.

It will also be seen that the flange 13 is spaced from the upper edge 8 of the wall 6 in order that a saturated felt strip 14 will contact with the portion of the edge of a floor board in order that the edge may be lubricated to prevent noises. It will also be seen that as the U-shaped member is forced between adjacent edges of pair of floor boards, the wall 6 is snapped into place within the socket 10 of one board and the pressure of the member 6 will maintain the boards in a predetermined spaced relation and prevent rattling of the boards.

The member 13 provides a cover to prevent dust and other foreign matter from contaminating the lubricant in the felt strip 14. It will also be noted that the opposite ends of the U-shaped member 4 are brought together and sealed in any approved manner to prevent the loss of lubricant at these points. The felt washer, by means of capillary attraction, will raise the oil from the well formed in the U-shaped member and thoroughly lubricate the edges of the floor board to accomplish the result intended for the device.

What I claim is:

1. A binding strip for automobile floor boards comprising an inverted U-shaped channel member having a wall adapted to be fixed to an edge of the floor board, the other wall having less height than the fixed wall, the upper edge of the fixed wall having

- 2
- an extension bent to form a cover for the channel member, and a felt strip in the channel member saturated with oil.
2. A binding strip for automobiles floor boards comprising an inverted U-shaped channel member having a wall adapted to be fixed to an edge of the floor board, the other wall having less height than the fixed wall, the upper edge of the fixed wall having an extension bent to form a lateral flange, the extension being returned upon the flange to form a cover.
3. A binding strip for automobile floor boards comprising an inverted U-shaped channel member having a wall adapted to be fixed to an edge of the floor board, the other wall having less height than the fixed wall, the upper edge of the fixed wall having an extension bent to form a cover for the channel member, and a felt strip in the channel member saturated with oil and projecting above the second wall for engagement with an edge of the floor board.
4. A binding strip for floor boards of a vehicle comprising an inverted U-shaped
- channel member adapted to contain a lubricant, one wall of the channel member of less height than the other wall whereby a portion of the edge of the floor board is exposed to the interior of the channel member, a felt strip in the channel member and adapted to supply the lubricant to an edge of a floor board where it contacts with the same.
5. A binding strip for floor boards of a vehicle comprising an inverted U-shaped channel member having a wall adapted to be fixed to an edge of a floor board, a second wall having less height than the fixed wall, the upper edge of the fixed wall having an extension bent at right angles and adapted to be seated upon the upper surface of the floor board, an extension bent upon the flange located over the channel member to form a cover, the outer free end of the cover being returned upon itself and adapted to engage the upper surface of an adjacent floor board, and a felt strip in the channel member saturated with oil.

JAMES MADISON JACKSON.
